UNITED STATES PATENT OFFICE.

ARTHUR H. EDDY, OF WINDSOR, CONNECTICUT, ASSIGNOR OF ONE-HALF
TO CHARLES E. SHEPARD, OF HARTFORD, CONNECTICUT.

REGULATING-VALVE.

No. 853,504.

Specification of Letters Patent.

Patented May 14, 1907.

Application filed January 6, 1906. Serial No. 294,876.

To all whom it may concern:

Be it known that I, ARTHUR H. EDDY, a citizen of the United States, residing at Windsor, in the county of Hartford and State of Connecticut, have invented a new and useful 5 Regulating-Valve, of which the following is a specification.

This invention relates to a valve which is designed to regulate the flow of water or 10 other fluid which is used for absorbing heat from other liquids or gases or apparatus which it is necessary or desirable to keep cool, by the temperature of the cooling fluid in order to effect an economy in the use of the 15 cooling fluid, and it is particularly adapted for controlling by its own temperature the flow of water which is employed to cool the condenser of a refrigerating plant, a large item of expense in the operation of which is for the 20 condensing water which is necessarily used.

The object of the invention is to construct a simple, efficient, and sure valve which will automatically regulate the flow of water, or 25 other cooling fluid, according to its own temperature, that is, increase the flow if not enough cooling water or other fluid is being used and it heats above normal, and reduce the flow if the temperature drops below normal as a result of the use of too much water 30 or other cooling fluid, and to effect the stopping of the motor which is used to operate the system in which the valve is placed if the temperature of the cooling water or other fluid rises too high or if the flow of water 35 ceases, and to effect a starting up of the motor when the temperature of the cooling water or other fluid drops to normal or if the flow having been stopped again starts.

The embodiment of this invention has a 40 valve with ports the area of which depends upon the density of a confined fluid which is subjected to the flow of water or other cooling fluid, and has electrical contacts adapted to be connected with suitable motor controlling apparatus, that are engaged when the predetermined extremes of expansibility of 45 the confined fluid are reached.

The figure of the drawing shows a central vertical section of one form of valve which 50 embodies the invention.

In the water-way in the body 1 of the form of valve illustrated, which may be cast to shape of iron, brass, bronze, or any other suitable metal, is a drum which is preferably

formed of an inner tube 2 and an outer tube 55 3. The outer tube is a little less in diameter than the interior of the body and the inner tube is open at the top and bottom, in order that the water or other cooling fluid which flows through the body may pass around the 60 outside of and through the interior of the drum. The space between these tubes is closed at the bottom by a ring 4 and at the top by a ring 5. Spanning the ring at the top of the drum is a bridge 6 with a passage 7. 65

In a chamber above the body is an expansion diaphragm 8. This diaphragm is connected with the bridge across the ring at the top of the drum by a tube 9 in such manner that the passage in the bridge communicates 70 through the tube with the interior of the diaphragm.

In the lower part of the body is a cylinder 10 containing a freely movable piston valve 11. Around the cylinder is a port opening 75 12 and through the walls of the piston and co-operating with the port opening in the cylinder are ports 13. The piston valve is by a rod 14 connected with a spider 15 that is attached to the ring at the bottom of the 80 drum. The joint between the piston rod and piston valve is desirably made somewhat loose in order that there may be no binding of the parts.

A plug 16 which can be easily removed 85 to permit free access to the valve cylinder is screwed into the opening at the bottom of the body. This plug is threaded so that the valve may be readily attached to the pipe from the system containing the water or 90 other fluid which is used for cooling purposes and the flow of which is to be regulated by its own temperature. The lower part of the outlet 17 is threaded for the attachment of a pipe which is used for conducting the water or other cooling fluid to any 95 desired locality. The top of this outlet is preferably open in order to allow the cooling fluid to overflow rather than flood the diaphragm chamber should the outlet for any 100 reason become closed or choked.

The top of the diaphragm is loosely connected with an adjusting screw 18 which extends through the cap 19 which forms the top of the diaphragm chamber. By 105 turning this screw the location of the diaphragm and the normal relation of the ports in the piston valve and the port open-

ing in the valve cylinder are adjusted. When adjusted the nut 20 is set up to clamp the screw against further movement.

Pivotedly supported by the base 21 of the 5 diaphragm chamber is a lever 22. The inner end of this lever extends beneath a hub 23 that is attached to the bottom of the dia- phragm and the outer end of this lever bears an insulated electrical contact 24. Extend- 10 ing outwardly from the base is an arm 25 bearing an insulated electrical contact 26, the position of which is adjusted by the screw 27. Extending outwardly from the cap is an arm 28 bearing an insulated elec- 15 trical contact 29, the position of which is ad- justed by the screw 30. These electrical con- tacts may be connected with circuit wires leading to any common form of electrical apparatus for controlling the operation of 20 a motor used in the system. It is desirable to connect a tension spring 31 which may be adjusted by turning the screw 32 with the lever for the purpose of counterbalancing the weight of the drum and connected parts.

25 The space between the tubes which forms the drum in the water-way in the body of the valve is filled with some fluid which has a low boiling point. This fluid may be sul- 30 furic ether under about five pounds absolute pressure, which substance under this pres- sure boils at approximately fifty degrees and has considerable expansive power. If this valve is to be used in a refrigerating system the inlet is connected with a pipe that leads 35 from the condenser and the outlet is connected with a pipe that leads to the receptacle for the cooling water. The circuit wires from the electrical contacts may be connected with a controller of common form 40 which controls the operation of the motor which actuates the pump that circulates the refrigerating fluid.

45 The water from the condenser passes upwardly into the body through the port oper- ating in the cylinder and ports in the piston valve and up around the outside and through the interior of the drum containing the ex- pansible fluid and through the outlet to the waste pipe. If sufficient water is flowing 50 through the condenser to keep the tempera- ture properly reduced the temperature of the water will have no abnormal effect on the fluid in the drum and consequently the pis- ton valve will remain with its ports open to 55 the predetermined normal degree. If there is not sufficient water flowing to properly re- duce the temperature of the condenser this water will become warmed and its heat will cause the fluid in the drum to expand and 60 the expansion diaphragm to open and force the piston downwardly into the cylinder so as to enlarge the area of the ports and allow more water to flow through the valve and consequently the water to flow faster through 65 the condenser. If too much water is flowing

its temperature will be below normal and this low temperature will cause a contraction of the fluid in the drum and a consequent closing of the diaphragm which will lift the piston valve and reduce the area of the ports 70 so that less water can flow through the valve and consequently through the condenser.

If the condenser water should become ab- 75 normally hot as a result of requiring it to do too much work or the cessation of flow of water from the source of supply to the con- denser, the heat will expand the diaphragm to such an extent that the circuits to the controller which will cause the motor which operates the system to stop will be closed. 80 After the motor has been stopped when the temperature again falls to the low point the circuit to the controller which will start up the motor will be closed.

The invention claimed is:—

85 1. A thermostatic fluid regulator having a body with a fluid-way through the body, a valve for regulating the area of the opening to the fluid-way, a drum containing an ex- pansion fluid located in said fluid-way and exposed to the fluid immediately it passes the valve, a stem connecting the drum and valve, and a hollow diaphragm located above and out of the fluid way attached to and having its interior communicating with the 95 drum, substantially as specified.

2. A thermostatic fluid regulator having a body with a fluid way through the body, a valve for regulating the area of the opening to the fluid-way, a drum containing an ex- 100 pansion fluid located in said fluid way and exposed to the fluid immediately it passes the valve, a stem connecting the drum and valve, a hollow diaphragm, adjustable means supporting said diaphragm above and out of 105 the fluid-way, and means connecting the interior of the diaphragm with the interior of the drum, substantially as specified.

3. A thermostatic fluid regulator having a body with a fluid way through the body, a 110 cylindrical valve casing with ports at the lower end of the body, a piston valve in the valve casing and having ports arranged to co-act with the ports through the casing, a drum containing an expansion fluid located 115 in said fluid way and exposed to the fluid immediately it passes the valve, a stem connecting the drum and piston valve, and a hollow diaphragm located above and out of the fluid-way attached to and having its 120 interior communicating with the drum, sub- stantially as specified.

4. A thermostatic fluid regulator having a body with a fluid-way through the body, a valve for regulating the area of the opening to the fluid-way, a drum containing an ex- 125 pansion fluid located in said fluid-way and exposed to the fluid immediately it passes the valve, a stem connecting the drum and valve, a hollow diaphragm located above and out of 130

the fluid-way attached to and having its interior communicating with the interior of the drum, electrical contacts and means adapted to engage the contacts at a predetermined degree of expansion of the diaphragm, substantially as specified.

5. A thermostatic fluid regulator having a body with a fluid-way through the body, a valve for regulating the area of the opening to the fluid-way, a drum containing an expansion fluid located in said fluid-way and exposed to the fluid immediately it passes the valve, a stem connecting the drum and valve, a hollow diaphragm located above

and out of the fluid-way attached to and having its interior communicating with the interior of the drum, a lever adapted to be moved by the expansion of the diaphragm, an electrical contact carried by the lever, and electrical contacts adapted to be engaged by the lever contact at predetermined degrees of expansion of the diaphragm, substantially as specified.
